ATTORNEY

UNITED STATES PATENT OFFICE.

JOHN TINGLEY, OF PHILADELPHIA, PENNSYLVANIA.

HEEL-MACHINE.

SPECIFICATION forming part of Letters Patent No. 322,761, dated July 21, 1885.

Application filed November 8, 1884. (No model.)

To all whom it may concern:

Be it known that I, JOHN TINGLEY, a citizen of the United States, residing in the city and county of Philadelphia, State of Pennsylvania, have invented a new and useful Improvement in Machines for forming Boot and Shoe Heels, which improvement is fully set forth in the following specification and accompanying drawings, in which—

10 Figure 1 represents a front view of a machine for forming boot and shoe heels embodying my invention. Fig. 2 represents a partial plan view and partial horizontal section in line $x-x$, Fig. 1. Fig. 3 represents a 15 vertical section of a detached portion of the machine on an enlarged scale in line $y-y$, Fig. 2. Fig. 4 represents a vertical section of a detached portion of the machine on an enlarged scale on line $z-z$, Fig. 2.

20 Similar letters of reference indicate corresponding parts in the several figures.

My invention consists in a novel device or machine for forming or building up boot and shoe heels, as will be hereinafter fully set 25 forth.

Referring to the drawings, A represents the bed of the machine resting on suitable supports or frame. Secured to the upper face of the bed A are two parallel grooved plates, 30 B B', constituting a track or guideway for the sliding plate C, to which latter is secured by means of a boss, a, and set-screw b, a head, D, having a flange, e, on which is guided an annulus, E.

35 Rising from the plate C are springs c', which may be either of rubber or coiled wire, on which the annulus E is supported, said springs having fitted within them bolts d, which are connected with the plate C and pass freely 40 through the flange of the annulus E, thus securing the annulus to said plate C and permitting the annulus to lower when the springs are compressed.

F represents nail-drivers formed of a series 45 of fingers which, by means of a plate, e, are connected with the head D, said plate being perforated and serving to clamp the lower ends of the fingers to said head.

Fastened to the annulus E is a nail-block, 50 G, having vertical perforations or holes corresponding to the nail-drivers F and receiving the same; and attached to the block G, by

means of dowel-pins f, is a lift-mold, H, having a recess, g, for holding the lifts of which the heel is built up.

55

O represents a curb consisting of a perforated metallic block about three-eighths of an inch in height, having its inner face perpendicular and of the same size and form as the heel-seat die. The curb is attached to the 60 mold H by screws or otherwise, so as to be fitted with it in the operation of the device.

On the sliding plate C, alongside of the combined lift-holder and nail-driver just described, is another similar structure, differing, 65 however, in some of its features from the outer one, it having fewer nail-drivers, three being shown in the drawings, and the perforations in the nail-block also being less in number, corresponding to the nail-drivers.

70

On the top of the nail-block, instead of a mold, there is an annulus, O', having a recess, h, of a depth sufficient to receive the top or finishing lift, and of form corresponding to that of the heel-seat lift, and so placed as 75 to be in line therewith.

Suitably journaled in bearings on the frame of the machine is a shaft, J, carrying on one end a wheel and clutch mechanism, the latter being properly connected with a treadle, and 80 on the other a cam which operates a plunger or driver, K, which is suitably fitted in guides which are secured to said frame.

Depending from and attached to the driver K are prongs or forks L, which are adapted 85 to pierce the heel, for purposes to be herein-after explained.

Pivoted to the bed A is a stop, M, having one of its ends k curved or hooked, and provided with a handle, l. N represents an angle-block attached to the bed A, and provided with a screw, m.

For the purpose of adjustment, so as to accommodate the machine to heels of different thicknesses, washers n are placed, as required, 95 between the plate C and the head.

The operation of the machine is as follows: The lifts, except the finishing and the heel-seat ones, are placed in the recess g of the mold H, the heel-seat lift being pressed within the curb O, so as to be held firmly during the pressure and nailing, said parts being detached from the nail-block G, the holes of which are supplied with the necessary nails.

100

The mold and curb are then attached to the block G by means of the dowel-pins f, and the plate C is slid inward until the end bears against the screw m of the block N, which is 5 adjusted so that the mold H will register or be in proper position beneath the plunger or driver K. The shaft J is rotated, and the said plunger or driver K lowered by means of the cam on said shaft J, causing the parts 10 H, G, and E to be depressed on the springs C', whereby the nail-drivers F force the nails placed in the nail-block G into the lifts which are in the recess g, so that they are fastened together, leaving, however, the nails projecting 15 about one-eighth of an inch, also causing the prongs L to enter the upper lifts. The continued rotation of the shaft J raises the driver K and the under lifts of the heels, the latter being attached to the said driver by the prong 20 L having been inserted therein. The springs C', preferably formed of rubber, resist the power of the plunger until the leather is firmly pressed before the nails enter it, (the nail being shorter than the perforations holding 25 them;) then, being pressed, the leather is forced down upon the nails, which stand upon an inflexible base. The parts E, G, and H are readily returned by the said spring to their normal position when the plunger is raised. The sliding 30 plate C is then brought back far enough to come in contact with the curved end h of the stop M, which, by means of the handle l, may be swung in front of the said plate C, when the upper part of the second-lift holder 35 having the recess h', which contains the finishing lift, will be beneath the driver K. The shaft J is then rotated, and the driver K, having the partly-completed heel on the prong L, descending, forces down the parts of the finishing-lift holder, so that the finishing lift is fastened to the other part of the heel—the first stroke entering the finishing lift from above, while the three nails of the second driver enter from below. The farther rotation of the 40 shaft lifts the heel with the plunger, when it may be detached therefrom and the operation 45 repeated.

Having thus described my invention, what I claim as new, and desire to secure by Letters 50 Patent, is—

1. In a machine or device for building up boot and shoe heels, a sliding plate having thereon two combined lift-holders and nail-drivers, one of which is adapted to contain but a single lift, in combination with a plunger 55 having a prong, substantially as and for the purpose set forth.

2. In a machine for building up boot and shoe heels, a nailing device composed of a head, D, having a flange, an annulus, E, guided 60 on said flange, springs C', supporting said annulus, and nail-driver F, secured to said head D, substantially as and for the purpose set forth.

3. A combined lift-holder and nailing device composed of the springs C', annulus E, head D, having flange, and provided with nail-drivers F, nail-block G, lift-mold H, having recess g, and curb O, all of said parts being arranged and combined substantially as and 70 for the purpose set forth.

4. In a machine for building up boot and shoe heels, a table, in combination with a sliding plate, having two combined lift-holders and nailing device thereon, a plunger, and 75 means attached to said table whereby the said combined lift-holders and nail-drivers may each be made to register with said plunger, substantially as and for the purpose set forth.

5. The bed A, in combination with the sliding plate C, carrying a combined lift-holder and nailing device, the plunger K, having prongs L, means for actuating said driver, the block N, having set-screw n, and a stop, M, substantially as and for the purpose set forth. 85

6. The sliding plate C, in combination with the nail-support D, annulus E, having flanges e, nail-drivers F, nail-block G, and lift-mold H, having recess h, said annulus G being loosely attached to said plate C by bolts having rubber springs thereon, substantially as and for the purpose set forth. 90

7. In a machine for forming boot and shoe heels, a detachable mold, in combination with a curb and an annulus having a recess, substantially as and for the purpose set forth. 95

JOHN TINGLEY.
